UNITED STATES PATENT OFFICE.

JOHN D. HILLIARD, OF GLENS FALLS, NEW YORK

SALVAGE APPARATUS.

1.262.341.

Specification of Letters Patent. Patented Apr. 9, 1918.

Application filed July 21, 1910, Serial No. 573,096. Renewed September 7, 1917. Serial No. 190,274.

To all whom it may concern:

Be it known that I, JOHN D. HILLIARD, a citizen of the United States, residing at Glens Falls, in the county of Warren and 5 State of New York, have invented certain new and useful Improvements in Salvage Apparatus, of which the following is a specification, reference being had therein to the accompanying drawing.

10 My invention relates to apparatus for and methods of penetrating and extending mechanical connections through media which in part or in whole are not directly accessible, and is particularly applicable to the
15 salvage of sunken vessels, the recovery of which constitutes its primary object.

Briefly stated, the apparatus comprises a self-propelled electromagnetic wheeled pilot carrying an air or water blast, a drag or follower also equipped with an air or water blast, but not self-propelled, auxiliary apparatus for controlling the pilot and the drag, and for supplying pressure to the blasts, and finally certain buoyant bodies adapted for attachment to a submerged hull by slings placed in position by the pilot or the drag, or both. The method of operation depends upon the utilization of electromagnetism in the wheels or body of the pilot to secure adhesion to a hull or other magnetic body, electric or hydraulic energy for propelling the pilot, and an air or water blast for clearing away obstructions during its progress.

ing away obstructions during its progress. As applied particularly to the raising of sunken iron vessels, my method contemplates first the passing of a drag rope or sling around the hull by means of the self-propelled pilot, which passes around one side of the hull beneath the keel and up the other side, the mud, gravel and other obstructions being cleared as the pilot progresses by means of the blast; second the passage of other slings around the hull by means of the drag; third the attachment of water-filled floats or caissons; and fourth the introduction of air under pressure to said floats or caissons so as to expel the water therefrom and produce the buoyancy necessary to raise the hull. It is to be understood of course that the electromagnetic pilot is only effective when used on vessels having hulls of magnetic material such as iron. The floats are preferably so proportioned that their lifting effect is somewhat less than the total weight of the hull submerged, so that it will not be possible for the latter to ascend on the run,

and I furnish the supplemental lifting power from a vessel on the surface of the water.

My invention is illustrated in the accompanying drawings in which— 60

Figure 1 is a plan view partly in section of my electromagnetic pilot.

Fig. 2 is a transverse section on the line 2-2 of Fig. 1.

Fig. 3 is a sectional view of the drag carrying one sling S' and drag rope f' and about to be propelled through the water on a previously applied sling S by the drag rope f , the water line being inverted. 70

Fig. 4 is a diagrammatic view showing the progress of the pilot around a submerged hull partly buried under mud and silt.

Fig. 5 is a similar view showing the slings in position and the floats on the surface of the water prior to being sunk. 75

Fig. 6 is a similar diagram showing the floats locked in their final position.

Fig. 7 is a diagram showing in outline a hulk being encircled with slings, the second sling being drawn into the position by means of the drag traveling on the first one. 80

Before proceeding to a specific and detailed description of the apparatus, the system and method may be generally stated as follows, reference being had to the drawings: 85

Figs. 1 and 2 show the pilot, which I may also call a self-propelled or traveling electromagnet. Its function, as already stated, is to cling to the hull of a vessel, while traveling over its surface, dragging a rope or sling f^2 behind it, and also dragging a cable containing the circuit wires through which its electromagnets are supplied with current, a hose conveying pressure for the blast, and also for its hydraulic motor, and the wires from a position indicator by which the progress of the pilot is shown to the operator. Under certain conditions the drag rope may be omitted, the cable being reinforced in such manner as to have sufficient mechanical strength for all purposes; and in some cases the hose may be omitted, and an electric motor inclosed in the casing for driving purposes, geared so as not only to turn the magnetized wheels, but also to work a pump and create a blast around the casing to clear away obstructions from the path of its travel.

Fig. 4 shows in dotted lines the progress

of the pilot around a submerged hull. It is first lowered on a straight line as indicated at P^0 , and by means of the position indicator to be described, the operator knows that it is swinging vertically. As it passes around into the successive positions P' , P^2 and P^3 , the position indicator shows the operator its successive changes of direction, and when it reaches the position P^2 , the float F can be shot through the hose pipe, and the central tube p of the pilot, emerging and rising to the surface by its own buoyancy, and carrying with it the line f .

Referring to Figs. 5 and 6, the floats or caissons C , C' are first fastened to the slings S and S' at the surface of the water, on opposite sides of the hulk, and the slings are passed through dogs D and D' , the former of which is clamped onto the sling S , and has a one way grip engaging the sling S' , while the latter, D' , is clamped to the sling S' and engages the sling S with its one way grip. The slings S and S' are drawn up as the floats C and C' are submerged, so that in the position shown in Fig. 6, the dogs lie on opposite sides of the hull, binding the two floats together as by a single sling, which however is doubled, as it should be, at the point v where it receives the thrust of the keel. The floats C and C' are provided with cushions or fenders B , B' , to protect both the hull and the floats from injury by distributing the pressure between them.

The general functions of the parts being now understood, Figs. 1 and 2 may be specifically described. The pilot P consists essentially of a metal casing (preferably non-magnetic) marked p' , rectangular in plan, and in cross section shaped substantially like the letter B, with a pair of iron axles or shafts p^2 , p^3 extending through it from side to side and capable of being polarized by their respective magnetizing windings p^{50} , p^{60} , each carrying at its opposite ends a pair of iron wheels p^4 , p^5 which thus constitute the pole pieces of an electromagnet. These wheels, as shown in Fig. 2, are somewhat larger in diameter than the casing, so that the latter will clear the surface upon which they travel.

Extending through the casing from end to end is the tube p , constituting a continuation for operative purposes of the pressure hose H , which is secured upon the protruding outer end of the tube by a coupling h . The tube p is provided with a gate valve p^{15} , by which it may be closed and all the pressure diverted through two lateral tubes p^6 and p^7 , to the runners p^8 , p^9 of the water motor whose shaft p^{10} carries a pair of worms p^{11} and p^{12} engaging the worm wheels p^{13} and p^{14} secured to the rotary axles or shafts serving as magnet cores p^2 and p^3 . The tubes p^6 and p^7 are alternately

closed by means of gate valves p^{19} and p^{20} , which in turn are controlled by a piston working in a hydraulic cylinder p^{21} with controlling tubes p^{22} , p^{23} leading to ports at opposite ends of the cylinder. The valve p^{19} in the main tube p is similarly controlled by a piston working in a hydraulic cylinder p^{16} , controlled through ports in its opposite ends which communicate with tubes p^{17} , p^{18} . Obviously, with pressure in the tube p from the hose H , the hydraulic engine for turning the wheels p^4 and p^5 may be started, stopped, reversed, and otherwise controlled at will, and the blast started or stopped as well, by opening or closing and thereby admitting pressure to or excluding it from the respective control tubes p^{17} , p^{18} , p^{22} and p^{23} . This opening and closing may be accomplished by carrying these tubes themselves through the cable heretofore mentioned, and along with the hose H , to the surface of the water, or they may be controlled locally in the casing p' by suitable electromagnets, and the circuits of these magnets can then be carried up through the cable and at the other end thereof joined to contacts in one or more switches, so that by simply turning the switches to register with the proper indication "Forward," "Reverse," "Blast," "Cut-off," the respective operations will be automatically performed.

In order that the operator may be kept apprised of the approximate location of the pilot, as shown at P^0 , P' , P^2 , P^3 in Fig. 4, I provide a position indicator, preferably with a hand floating over four electromagnets, by any one of which it may be attracted so as to point to the four indications "Descending," "Turning," "Horizontal," "Ascending." Of course these designations are arbitrary, both in number and in character, and may be made anything desired without affecting the invention. The wires from the four electromagnets of the indicator are carried through the cable to the pilot casing, wherein I mount a sensitive controller operated by gravity, which is designated by the letter Q in Fig. 2. It comprises an exhausted cylinder or sphere (the exhaustion however not being imperative) containing a small quantity of mercury and having four contact terminals extended through its walls, these being connected to the four indicator wires respectively, in such fashion that as the pilot tilts at different angles, different pairs of contacts will be bridged, or different individual contacts brought into connection through the mercury with a common return which may well be the body of the cylinder or sphere itself, the terminals in such case being properly insulated therefrom by glass, mica or other suitable bushings.

The machine thus described, while electromagnetic in its means of guidance by adhe-

sion, is hydraulic in every other respect. I can however make it electric in every sense, as already suggested, by inserting an electric motor in the casing in place of the runners p^8 and p^9 , the motor being suitably connected so that the direction of rotation of its armature may be reversed at will, and both worm wheels p^{13} , p^{14} thereby caused to reverse the direction of rotation of the driving wheels p^4 , p^5 on their respective shafts. Of course with such an arrangement, the valves p^{19} and p^{20} become superfluous, being replaced by controller contacts at the other end of the cable. The valve p^{15} however is of use in partially or wholly cutting off the blast from the main tube p , and diverting it into lateral channels, with any form of motor. It should be noted that the casing has outlets or exhaust openings such as p^{24} in Fig. 2, from which the water escapes after passing the runners p^8 , p^9 , under such pressure as may be predetermined in the design of the motor, and in conjunction with the direct blast through the tube p clears away sand, gravel, mud, silt and other obstruction, even small stones yielding as a rule when the pressure is raised sufficiently.

Referring now to Fig. 3, the drag or follower, which I may also call a mechanical sling placer, is in the form of a triangle T , composed of tubes t , t' and t^2 , with external blast nozzles t^3 , t^4 and t^5 , and internal nozzles t^6 , each of these having twin openings pointed in opposite directions except t^8 , which has three openings, so as to clear a path in advance of the member t as well as around the triangle. Water under pressure is introduced into the tubes through a hydraulic supply pipe connected with the hose H , and causes simultaneous blasts through all the nozzles as long as the pressure is maintained. At the two ends of the member t^2 parallel guide tubes t^9 and t^{10} are provided, and into these jets are also thrown from the tubes t and t' through openings t^7 and t^8 , the purpose of which is to keep the guide tubes clear of mud and the like, to permit the free passage of the chain cable or sling S . The upper guide tube t^9 is provided with two wheels t^{12} , to prevent undue friction and resistance to obstructions on the surface of the hull. f is a drag rope, the end of which is attached to an elongated float, preferably filled with air, indicated at F in Fig. 4. After the pilot has reached an advanced position, as for example that shown at P^3 in Fig. 4, the float F is inserted in the upper end of the downwardly extending hose H , into which it is drawn, and through which it pulls the rope f , by virtue of the impelling force of the stream of water through the hose. When the float reaches the pilot, it is shot through the central tube and discharged therefrom so that its buoyancy will carry it to the surface of the wa-

ter, dragging the rope behind it, as indicated by the dotted line in Fig. 4. The pilot may then be withdrawn if desired. The first cable or sling S is then bent onto a bight in the rope f , and by hauling on the float end of the latter, the cable is pulled through into position, while the continuous length of the rope f accompanies it. The relation of the drag, sling S' , and drag rope f' when about to be propelled through the water on the previously applied sling S by the drag rope f , is shown in Fig. 3, where the dotted line at the top of the figure represents the surface of the water into which the next rope f' and cable S' are about to be drawn as indicated by the arrows. This water line appears at the top because the figure is inverted. It should not be confused with the water line of Fig. 4 which is not inverted but is in a separate figure. The same general idea is represented also in Fig. 7. By drawing on the rope f , the drag T will travel on the cable S , drawing with it a second cable S' and a second rope f' , which are thus carried around beneath the hull at a fixed distance from and parallel to the first sling or cable S . When the drag reaches the surface of the water at the opposite side of the hull from which it entered, as for example at the point α in Fig. 4, it is detached from the chain cables S and S' and the ropes f and f' , and is placed in position on the first side of the hull with the cable S' passing through the guide tubes t^9 and t^{10} , and the rope f' fastened to the upper end of the triangle in place of the rope f , but in the same relation shown in Fig. 3, after which by drawing upon the rope f' , the drag T can again be pulled down beneath the hull and up on the opposite side, using the cable S' as a guide, and carrying with it a third cable and a third drag rope. This operation may be repeated as many times as desired, until a series of parallel slings or cables S , S' , etc., have been passed beneath the hull from bow to stern, or throughout any desired portion of the length. It will be observed that each chain cable when drawn into position, serves as a guide for the drag T in placing the next cable or sling.

It is thought that the mechanical features of the other parts of the apparatus will now be found sufficiently clear from the following statement of operation:

Referring to Fig. 4, H^x indicates the pilot cable to which reference has been made, containing the hose H , the pneumatic tubes or wires as the case might be for the motor valves p^{17} , p^{18} , p^{22} and p^{23} in Fig. 1, the wires for the electromagnets in the same figure, (the windings of which are indicated at p^{50} and p^{60}) and the wires from the gravity circuit closer or sensitive controller Q in Fig. 2. It is understood of course that if an electric motor is used instead of a hydraulic

motor, circuit wires will be required for this, instead of the pneumatic or hydraulic tubes for control. It should also be stated that I can dispense with the separate control wires or pressure tubes for the motor entirely.

The pilot is lowered from the surface of the water until it strikes the side of the hull as shown in Fig. 4, the water blast turned on, and the lowering continued so that the 10 wheels will take hold and commence to exert a pull on the cable. When this happens the operator will be instantly apprised of the fact, and to make this the more certain, I may provide a dynametric indicator which 15 will show the moment when the upward thrust of the blast in the water is overbalanced by the tractile effect of the rotating wheels on the hull. The blast may have to continue for some little time before the 20 wheels will take hold, but after they do, the cable is payed out and the pilot is permitted to travel downward until it begins to turn under the bends of the hull, when the cable is swung out as indicated by the dotted lines 25 H' , so as to prevent undue dragging resistance. The pilot then travels into the successive positions P' , P' , P^2 and P^3 each of which is announced to the operator by his 30 position indicator. The magnet cores and rotating polar wheels are kept highly magnetized, so as to afford sufficient adhesive power to enable the pilot to cross all such obstructions as bilge keels and the like.

The position P^3 having been reached, the 35 float F is introduced into the hose H by the operator, with the line f attached to it, and while the pilot remains adherent and in fixed position, the float is driven through the hose and through the pipe p in the pilot, 40 emerging by its own buoyancy as shown at F in Fig. 4, at a point on the surface of the water separated from its point of entrance by the beam or width of the hull.

Having recovered the float F , the operator 45 finds himself with a line around the hull, the current is then cut off from the magnets in the pilot, or the motor may be reversed by dropping the pressure as already stated, or otherwise, and the pilot is drawn backward 50 and finally after passing through the successive positions P^2 P' P^0 is raised to the surface of the water at its point of entrance, leaving the line f in position.

The line f is then bent onto the end of the 55 cable S preferably leaving sufficient trail rope behind the bend to parallel the cable, for attachment to the drag T as shown in Fig. 3. After the line f and sling S are drawn through, the operator has one sling or chain 60 cable and the drag rope around the hull. The trail portion of the rope is then bent onto the drag T as shown in Fig. 3, and the guide tubes t^9 and t^{10} passed over the end of the cable S and the latter secured so as to 65 serve as a guide for the drag. The hose H'

being coupled up to the pump, and the second chain cable S' and drag rope f' being attached to the drag T as shown, tension is then placed on the line f , now detached from cable S , in the direction of the arrow 70 in Fig. 3, and while the blasts from the several nozzles force away the surrounding material, the drag is hauled around the hull, carrying with it the second cable S' spaced apart from the first cable sling by the length 75 of the arm t' of the triangle, which may be made anything desired according to the character of the work and the number of slings required. It should be noted that in Fig. 3, as already stated, the drag, with the 80 ropes f and f' and the chain cables S and S' , are shown in the position of entering the water, but inverted. This same figure however may be taken as illustrating the position of the parts when the drag leaves the 85 water on the opposite side of the hull, also their position at all points in the journey around the hull. It should also be noted that the hose or water pipe H indicated in Fig. 3 may or may not be the same hose H 90 used with the pilot and shown in Figs. 1 and 2. The same designating letter is employed because the primary function of the hose in each case is practically the same.

This operation is repeated until as many 95 slings are in position as desired, and the slings are then taken in pairs, and the opposite ends of each pair are secured as shown in Fig. 5 to the floats or caissons C and C' respectively. As all the pairs are the same, 100 the further operation will be understood by reference to the single pair shown in Figs. 5 and 6. Of these, the cable S carries a dog D , which is clamped upon it at a point contiguous to the float C , leaving enough slack 105 between the dog and the float to prevent undue lateral strain in lifting. The dog has a tubular portion through which the end of the other sling S' is passed, retraction thereof being prevented by a jamming device of 110 suitable character, such as a roller working on an inclined plane in the tube, an upwardly pointing pawl pivoted in the tube and spring pressed against the sling cable, an upwardly rising cam, or the like. A 115 similar dog D' is clamped on the sling cable S' , and receives the hauling end of the cable S .

Now, with all the pairs of cables connected in this way, the hauling ends S^{11} and S^{12} 120 are brought inboard on the operating vessel and either manned, or attached to winches for hauling up. The floats C and C' are fitted with cocks and connected by pipes to air pumps on the operating vessel. The 125 cocks are first opened, and the floats are flooded, whereupon tension is put simultaneously on all the hauling parts and as the floats sink they are hauled down along the opposite sides of the hull, guided in their 130

descent by the dogs traveling on the hauling parts, until they reach the position shown in Fig. 6. All that is necessary to retain this position is to slacken up the tension, when the dogs immediately lock, and the floats are held in the position shown with the hull in a cable-formed cradle between them. The air pumps are then started, and the cocks being opened, air under pressure is forced 10 into the floats and the water expelled therefrom, until full buoyancy is attained. The fenders B and B' are preferably placed in position on the floats before they are sunk, and prevent injury to the hull by distributing the pressure under flotation.

As already stated, I prefer the lifting power of the floats C and C' to be a little less than necessary to raise the hull, so that the latter will not come up with a run. It 20 will be observed that further tension on the winches or by hand on the hauling parts of the cables S^a and S^b will no longer pull down the floats, because of their buoyancy, but will be resisted and transferred to the 25 hull, so that double the lifting power of the floats may be applied to the hull, which leaves an ample margin for control.

In practice, I prefer to employ a pair of barges buoyed or moored on opposite sides 30 of the sunken hull, and operate from one to the other, the hull finally rising between them. The slings can then be attached on both sides to the barges and if the hull is tight, or can be made so, the water can be 35 pumped out and suitable repairs proceeded with, or moved to any suitable location for the work in hand.

The reason for preferring a surface auxiliary lift is this, that with an inflexible 40 float, even if a portion of the water were left therein, the air pressure being constant, as soon as the hull commenced to rise the remaining water would be expelled by the air pressure in excess of the back pressure 45 due to the lessening hydrostatic head. This could be controlled by leading the expelled water to the surface through a hose and controlling the outlet, but I prefer the method of absolute regulation by leaving a 50 margin for the auxiliary lift.

It will be observed that at every step in my method, the engineer in charge has perfect control, and by watching his indicators, can bring the hull to the surface without 55 shock and without risk of losing a cable or straining any apparatus. As the hull approaches the surface, the pull on the submerged floats increases, and on the hauling parts decreases, until the surface of the 60 water is reached, when the entire weight is carried by the submerged floats.

To facilitate this work and give positive knowledge of what is being done on the hull, it is my intention to use a cable supported, motor operated, pressure balanced,

diving bell equipped with the necessary safety devices and operating, communicating, and observation appliances, for making the descent, noting operations and acting thereon.

Having thus described my invention what I claim and desire to secure by Letters Patent is—

1. A pilot device comprising a distant operated motor, propelling means driven by 75 the motor, magnetizing coils for the propelling means adapted when energized to polarize the same and thereby to produce adhesion thereof to the surface traveled over, and conductors for conveying energy 80 in suitable form to the motor and to said magnetizing coils respectively, and means for causing fluid jets to clear a path for the pilot device, substantially as described.

2. A pilot device comprising a motor, propelling wheels driven thereby, magnetizing windings for the wheels adapted when energized to polarize the same and thereby to produce adhesion thereof to the surface 85 traveled over, means for supplying energy 90 to the motor and the windings respectively, and means for clearing a path for the pilot device, substantially as described.

3. A pilot device comprising a motor, a casing containing the same, propelling 95 wheels mounted on the casing, magnetizing windings for the wheels carried within the casing adapted when energized to polarize the wheels and thereby to produce adhesion thereof to the surface traveled over, means 100 connected with the casing for supplying energy to the motor and the windings respectively, and means for clearing a path for the pilot device, substantially as described.

4. A pilot device comprising a reversible 105 motor, a casing containing the same, propelling wheels mounted on said casing, magnetizing coils for said wheels inclosed within the casing adapted when energized to polarize the wheels and thereby to produce 110 adhesion thereof to the surface traveled over, means for supplying energy to the motor and the magnet windings respectively, controlling means for the motor, said supply and controlling means being extended to an 115 operating point remote from the pilot, and means for causing fluid jets to clear a path for the pilot device, substantially as described.

5. A pilot device comprising a motor, 120 means for clearing a path for said device, a casing therefor, propelling wheels mounted on the casing and composed of magnetic material, magnet windings adapted when energized to magnetize the wheels, and a cable 125 attached to the casing and adapted to be drawn after the pilot in its travel, said cable containing means for conveying energy to the motor, means for conveying energy to the magnet windings respectively, and 130

means for controlling the supply of energy to the motor so as to determine the direction of the drive, substantially as described.

6. A pilot device comprising a hydraulic motor, a casing therefor, hydraulically operated propelling wheels mounted on the casing and connected to be driven by the motor, and a hose pipe attached to the casing and adapted to be drawn after the pilot in its travel, together with a source of supply, substantially as described.

7. A pilot device comprising a hydraulic motor, a casing therefor, hydraulically operated propelling wheels mounted on the casing and connected to be driven by the motor, and a hose pipe attached to the casing and adapted to be drawn after the pilot in its travel, together with a source of supply for the motor, and means for controlling the same at a point remote from the pilot, substantially as described.

8. An apparatus of the character described comprising an electromagnet adapted to run upon and cling to a magnetic surface, a distant controlled independently operating motor for propelling the same over said surface, means for supplying energy to the magnet and to the propelling means respectively, and means to reverse the propelling means, substantially as described.

9. In salvage apparatus, a distant controlled pilot, a drag rope adapted to be placed in position by said pilot device, a sling cable adapted to be drawn into place by said drag rope, a drag or cable placer adapted to travel along said sling cable, and means for producing jets or blasts in the path of said cable placer, whereby an open space is maintained for the passage of cable after having been cleared by the pilot.

10. A salvage apparatus comprising a blast nozzle through which fluid under pressure may be applied to a bed upon which a vessel rests so as to form a path thereunder, and an hydraulic motor device supporting, directing, and propelling said nozzle along the path which the blast of the nozzle creates.

11. A pilot device comprising a hollow casing having jet openings therein, together with means connecting the casing with a source of fluid under pressure whereby fluid blasts are issued from said jet openings, and a distant controlled motor device supporting, directing, and propelling said casing, whereby the apparatus is adapted to travel in the path cleared by the blasts from said jet openings.

12. An apparatus of the character described comprising an electromagnet adapted to roll upon and cling to a magnetic surface, and a casing surrounding said elec-

tromagnet and having jet openings, together with means to supply fluid under pressure to said casing to create blasts from said jet openings.

13. A pilot device for salvage work, comprising a casing, a motor adapted to drive the pilot, a blast opening in the casing with means for supplying fluid under pressure thereto, and a float adapted to be forced to and through the casing by the stream of fluid, substantially as described.

14. In salvage apparatus, a pilot with a blast tube and pressure hose, means to propel the same beneath the hull of a sunken vessel, and a float with line attached adapted to be forced through the hose and blast tube to carry the line under and around said vessel, substantially as described.

15. An apparatus of the character described comprising an electromagnet having rotatable pole pieces adapting said magnet to cling to and run upon a magnetic surface, and means for rotating said pole pieces while the electromagnet is energized, whereby the apparatus may be propelled as a unit over any magnetic surface, together with a fluid blast nozzle supported and directed from said apparatus.

16. An apparatus of the character described comprising a fluid blast nozzle, means for supplying pressure thereto to produce said blast, and a traveling self-propelling submarine vehicle device supporting and directing said nozzle, said nozzle adapted to clear a path for said self-propelled vehicle.

17. An apparatus of the character described comprising a blast nozzle, together with means for supplying fluid pressure thereto to produce said blast, and a self-propelled submarine vehicle supporting and directing said nozzle and provided with means for holding itself against the hull of a ship, said nozzle being adapted to clear a path for said vehicle whereby the latter may traverse the hull of a ship.

18. An apparatus of the character described comprising a wheeled vehicle adapted for submarine use, magnetic traction devices acting through the wheels of said vehicle to hold the same to a magnetic surface, and a blast nozzle supported and directed from the front of said vehicle, whereby a path may be cleared and said vehicle may traverse the magnetic hull of a ship while clinging thereto.

In testimony whereof I affix my signature in presence of two witnesses.

JOHN D. HILLIARD.
